UNITED STATES PATENT OFFICE.

DANIEL H. TALBERT, OF INDIANAPOLIS, INDIANA.

GAME APPARATUS.

SPECIFICATION forming part of Letters Patent No. 730,987, dated June 16, 1903.

Application filed January 23, 1903. Serial No. 140,308. (No model.)

To all whom it may concern:

Be it known that I, DANIEL H. TALBERT, a citizen of the United States, residing at Indianapolis, in the county of Marion and State 5 of Indiana, have invented a new and useful Game Apparatus, of which the following is a specification.

This invention relates generally to game apparatus, and specifically to that class in 10 which balls rolled by hand are employed for tripping objects located at the end of an alley or table after the manner of ordinary tenpins.

The object of the present invention is to 15 provide a game apparatus of the above description which while partaking of the features of an ordinary tenpin-alley will differ therefrom in the manner of playing the game and in the character of the objects employed 20 to be struck by the balls, the differences presented operating to impart added interest to the sport and the exercise of great skill in accomplishing the winning of a game.

A further object is to obviate the necessity 25 of the employment of an attendant for setting up the devices to be struck or for returning the balls to the player.

With these and other objects in view, as will appear as the nature of the invention is 30 better understood, the same consists in the novel construction and combination of parts of a game apparatus, as will be hereinafter fully described and claimed.

In the accompanying drawings, forming a 35 part of this specification, and in which like characters of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof.

In the drawings, Figure 1 is a view in perspective of a game apparatus constructed in accordance with the present invention. Fig. 2 is a view in front elevation of the paddles or pins, on an enlarged scale. Fig. 3 is a view in vertical longitudinal section, taken on the 45 line 3 3 of Fig. 2 and looking in the direction of the arrow thereon. Fig. 4 is a modified form of locking means for the paddle.

The present invention is an improvement upon a game apparatus for which Letters Patent were issued to me December 2, 1902, as 55 No. 714,969, and the improvements herein relate more specifically to the novel arrangement of the pin or paddle mechanism and means for setting the same.

Referring to the drawings, 1 designates the 60 alley or table, constructed in the usual or any preferred manner and mounted upon a base 2, the latter being supported in any suitable manner, as by legs 3, as shown in Fig. 1, and secured at its rear to posts 4 and 5, the table 65 being of less width than the base to present two gutters, as usual, the balls being prevented from rolling off the gutters by vertical side pieces 6.

At the rear of the alley is provided the usual 70 cushion 7, which terminates at its lower end in a transversely-disposed chute 8, the bottom of which is inclined and merges into a race 9, leading to the front of the alley, the race and chute operating as an automatic 75 means for returning the balls to the players, thereby obviating the necessity of the employment of an attendant for the purpose. The description thus generally given is of one 80 form of alley adapted for use in connection with the present game and is in all substantial respects the same as that shown in the patent referred to; but it is to be understood that the same may be otherwise constructed and still be within the scope of the invention. 85

Supported at a suitable distance above the table at the rear end of the alley is a deck 10, the body or bottom portion of which serves the dual function of a means for supporting the pins or paddles 11 and also as a cushioning device for the upper ends of said pins by having secured to it a transverse cushion 12. (Clearly shown in Figs. 2 and 3.) The upper portion of the deck constitutes a figure-board 12^a and is by preference scalloped for purposes of ornamentation, as shown in Fig. 2. The rear portion of the deck is provided with an upstanding flange 13, the function of which will presently appear. Secured to the front side of the deck are two angle-irons 14, through 90 the lower portions of which pass a rod or bar 15, upon which are pivotally mounted in any preferred manner the pins or paddles 11, constituting the objects to be struck, there being 95 100

shown in this instance but five of these devices; but it is to be understood that this number may be increased if found necessary or desirable. The paddles are by preference 5 constructed of wood and have their lower ends cushioned at 16, preferably with heavy leather, the lower front end of the paddle being cut away to form a recess between which and the leather cushion is disposed a rubber 10 cushion 17, the latter being held secured to the paddle by screws or bolts 18. The paddles are eccentrically pivoted with the greatest weight at the upper ends, or, in other words, are top counterweighted, as defined from the 15 paddles of the patent referred to, which are bottom counterweighted—that is, with the greatest weight at the bottom—and by this arrangement when tripped they will automatically remain in a horizontal plane, thereby 20 avoiding the necessity of the employment of any holding means for keeping them in this position, such as is shown in the patent referred to. This is of advantage, inasmuch as it dispenses with the employment of such 25 holding device, which in practice has been found to groove the lower ends of the cushions, so that in a short time such devices cease to be operative for holding the pins in their tripped position. This necessitates 30 the provision of new cushions, resulting in considerable expense, trouble, and annoyance. Furthermore, owing to the violent impact between the springs constituting the holding devices these latter frequently break, 35 and thus interfere with the playing of the game. As shown in Fig. 2, the lower ends of the paddles are reduced in width in order that unless a ball strikes fairly between two of them only one will be tripped, it being a de- 40 sideratum and necessary to make a score that at least two of the paddles be tripped with one ball, for under the rules of the game unless all of the paddles are tripped the player does not score. Under some conditions it 45 might be desirable to have the lower ends of the paddles arranged at such distance above the alley as to render it possible to trip only one paddle, and this is effected by adjusting mechanism, presently to be described. The 50 upper or broad end of the paddles bear each a number, the highest numbers in this instance being borne by the two outside paddles and the lower numbers by intermediate ones, the center paddle bearing the lowest, 55 the reason for this arrangement being that it is easier to strike an intermediate paddle than a corner one, and thus the more expert the player is the higher will be his score. As a 60 means for holding the paddles in operative 65 position a locking device 19 is combined with each paddle and comprises an arm 20, the forward end of which is downturned, as at 21, to hook over the upper edge of the paddle, as clearly shown in Fig. 3. These arms extend 70 through orifices 22 in the deck above the cushion 12 and project rearward beyond the flange 13, and each has connected with it the

lower end of a coiled spring 22^a, the upper end of which has connected with it an adjusting-bolt 23, which passes through a plate 24, 70 secured to the flange, a nut 25, screwed on each bolt, serving to place the spring under the requisite tension. The spring operates to hold the outer hooked end 21 down in the position shown in Fig. 3, and in order that it 75 may yield when the paddle is struck the orifice is made of sufficiently greater size than the locking device to permit it to rise, thus to free the paddle. The locking device is held in position upon the deck by a pin 25^a, 80 loosely seated in an orifice in the base portion of the flange 13 and in the deck.

One of the essential features of the present invention is the provision of means for causing the paddle when tripped gradually to stop, 85 and thus obviate jar and impact, and this is effected by a combined buffer and paddle-setting device 26, hinged to the lower portion of the deck at 27—in this instance by ordinary strap-hinges, although, if preferred, other forms of hinges may be employed. To permit the said device to occupy a position substantially at right angles to the deck, and thus present an effective stop to the paddles, the lower end of the deck and the outer end 95 of the said device are beveled, as clearly shown in Fig. 3. The under side of the buffer and paddle-setting device has combined with it a cushion 28, against which the paddle is adapted to strike when tripped, as indicated by dotted lines in Fig. 3. The cushion 28 projects some distance beyond the surface of the paddle-setting device in order that when struck by a tripped paddle it will gradually yield, and this causes the paddle to come 105 to rest without jar or impact. To hold the paddle-setting device in the position shown, a coiled spring 29 is provided, one end of which is secured to the end of the buffer at 30 and the other end to the back of the deck, 110 as indicated by dotted lines in Fig. 2. To effect return of the paddles to their normal position after having been tripped, a cord or wire rope 31 is employed, one end of which is secured at 32 to the end of the buffer, 115 thence is passed through an eye 33, secured to a part of the alley, and extends back to the front of the alley, where it is connected with a lever 34, pivoted adjacent to the alley. It will be seen that by drawing the lever backward the buffer will be drawn down, and thereby automatically effect resetting of the 120 paddles.

To effect adjustment of the deck with relation to the alley, thus to render the device 125 applicable for playing with balls of different sizes, the posts or uprights 4 and 5 are provided with vertical slots 35, through which pass bolts 36, carried by the deck, nuts 37, turned on the ends of the bolts, serving to 130 hold the deck in the proper adjustment, it being seen that by loosening these nuts the deck and width of the paddles may be raised or lowered for the purposes designed.

The form of apparatus herein shown will be found thoroughly effective in accomplishing the objects sought; but it will be obvious that in its construction various changes in the different parts thereof may be resorted to according to the tastes of the builder, and for this reason it is to be understood that this invention is not to be limited to the precise mode of construction and manner of arrangement of the parts herein described and shown, as these may be widely departed from without changing the spirit or sacrificing any of the advantages of the invention.

In the modification shown in Fig. 4 the arm 15 which engages the upper ends of and locks the paddles is controlled by the spring 22^a, as in Fig. 3, and in addition by a spring 38, seated in a socket 39 and adapted to be compressed when the latching end of the lever 20 rises to free the paddles, which construction dispenses with the pins 25^a for holding the lever.

Having thus described the invention, what I claim is—

1. A game apparatus comprising a table or 25 alley, a deck arranged on a plane above the rear end thereof, a plurality of pivoted pins or paddles supported by the deck and having a normal tendency to assume an approximately horizontal plane and an element 30 adapted to cushion the paddles when struck and to return them to their normal positions.

2. A game apparatus comprising a table or 35 alley, a deck arranged on a plane above the rear end thereof, a plurality of top-counterweighted pivoted pins or paddles supported by the deck, means for holding the paddles in normal or vertical position, and an element carried by the deck to cushion the paddles and to return them to their normal positions when tripped.

3. A game apparatus comprising a table or 45 alley, a deck arranged above the same, a plurality of top-counterweighted pins or paddles pivoted supported by the deck, and a paddle-setting device provided with a buffer.

4. A game apparatus comprising a table or 50 alley, a vertically-adjustable deck, a plurality of top-counterweighted paddles supported by the deck, and a paddle-setting device provided with a buffer.

5. A game apparatus comprising a table or 55 alley, a deck arranged on a plane above the rear end thereof, a plurality of paddles pivotally supported by the deck and having a normal tendency to assume an approximately horizontal plane, a paddle-setting device provided with a buffer, and means operable from the front of the table or alley to actuate the 60 said device thus to effect setting of the paddles.

6. A game apparatus comprising a table or 65 alley, a deck arranged on a plane above the rear end thereof, a plurality of paddles pivotally supported by the deck and having a

normal tendency to assume an approximately horizontal plane, a paddle-setting device supported by the deck and provided with a buffer, and means operable from the front of the table or alley to rock the said device, thus to 70 effect setting of the paddles.

7. A game apparatus comprising a table or 75 alley, a plurality of top - counterweighted paddles arranged adjacent to and supported above one end thereof, and a paddle-setting device, provided with a buffer, arranged in rear of the paddles.

8. A game apparatus comprising a table or 80 alley, a deck arranged at the rear end thereof and having its front provided with numbers, top-counterweighted paddles pivotally supported by the deck and bearing numbers corresponding to those thereon, means operating automatically to hold the paddles in vertical position, a paddle-setting device provided with a buffer, and means operable from the front of the alley to actuate the setting device.

9. A game apparatus comprising a table or 85 alley, an adjustable deck arranged at the rear end thereof and supporting a plurality of pivoted top - counterweighted paddles, a paddle-setting device pivoted to the deck in rear of the paddles and occupying a position normally substantially at right angles there- 95 to, and a buffer carried by the said device.

10. A game apparatus comprising a table or 100 alley, a deck arranged at the rear end thereof and including means for holding the same at any desired adjustment with relation to the 105 alley, a plurality of top-counterweighted paddles pivotally supported by the deck, and a paddle-setting device, provided with a buffer, pivotally supported by the deck and occupying a position normally substantially at right 105 angles to the paddles.

11. A game apparatus comprising a table or 110 alley, a deck arranged on a plane above the rear end thereof and provided with locking devices, a plurality of top-counterweighted 115 paddles pivotally supported by the deck and held normally in vertical position by the locking devices, and a paddle-setting device carried by the deck and provided with a buffer.

12. A game apparatus comprising a table or 120 alley, a deck arranged on a plane above the rear end thereof and provided with cushioning means, a plurality of top-counterweighted paddles pivotally supported by the deck, spring - controlled locking devices arranged 120 above the paddles, and a paddle-setting device pivotally supported by the deck and provided with a buffer.

In testimony that I claim the foregoing as my own I have hereto affixed my signature in 125 the presence of two witnesses.

DANIEL H. TALBERT.
